US00D718336S

(12) **United States Design Patent**
De Iuliis et al.

(10) **Patent No.:** **US D718,336 S**
(45) **Date of Patent:** **** Nov. 25, 2014**

(54) **COMPONENT FOR AN ELECTRONIC DEVICE**

- (71) Applicant: **Apple Inc.**, Cupertino, CA (US)
(72) Inventors: **Daniele De Iuliis**, San Francisco, CA (US); **Anna-Katrina Shedletsky**, Mountain View, CA (US)
(73) Assignee: **Apple Inc.**, Cupertino, CA (US)
(**) Term: **14 Years**
(21) Appl. No.: **29/476,037**
(22) Filed: **Dec. 10, 2013**

Related U.S. Application Data

- (63) Continuation of application No. 29/452,805, filed on Apr. 22, 2013, now Pat. No. Des. 695,316, which is a continuation of application No. 29/431,557, filed on Sep. 7, 2012, now abandoned.

(57) **CLAIM**

The ornamental design for a component for an electronic device, as shown and described.

DESCRIPTION

FIG. 1 is a top rear perspective view of a component for an electronic device showing our new design;

FIG. 2 is a bottom front perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.
